UNITED STATES PATENT OFFICE.

SYLVESTER W. SHELDON, OF NEW YORK, N. Y.

BARREL-SWING.

SPECIFICATION forming part of Letters Patent No. 246,824, dated September 6, 1881.

Application filed July 15, 1881. (No model.)

To all whom it may concern:

Be it known that I, SYLVESTER W. SHELDON, of the city, county, and State of New York, have invented a certain new and useful 5 Improvement in Barrel-Swings, of which the following is a specification.

In the accompanying drawings, Figure 1 is a side elevation of my improvement, illustrating its use. Fig. 2 is a plan view of the improvement, the position of the barrel being shown in dotted lines. Fig. 3 is a rear elevation of the pivoted support. Fig. 4 is a sectional elevation of the same, taken through the line *xx*, Fig. 2. Fig. 5 is a rear elevation 15 of the roller-support. Fig. 6 is a side elevation of the same.

Similar letters of reference indicate corresponding parts.

The object of this invention is to improve 20 the construction of the barrel-swing for which Letters Patent No. 227,848 were issued to me May 18, 1880, in such a manner as to make them more convenient and satisfactory in use.

The invention consists in a barrel-swing constructed with a curved bar having upon its 25 upper side notched projections, at its ends, and a radial rib at its center, and rollers pivoted between lugs upon its under side, at its ends, and a pivot at its center, the stationary socket 30 and the roller pivoted between the arms of a U-shaped bar, one arm of which is provided with a stirrup, whereby a barrel can be readily swung around upon the pivot, as will be hereinafter fully described.

35 A represents a bar, curved about upon the arc of an ordinary barrel, and having notched projections B upon the upper side of its ends to receive the chine of a barrel.

Upon the upper side of the center of the 40 bar A is formed a rib, C, for the chine of the barrel to rest upon. The rib C is formed upon a radius of the circle of which the bar A is a part. The rib C adapts the swing to be used with different-sized barrels, the chine of a 45 small barrel resting upon the outer part of the rib C, and the chine of a large barrel resting upon the inner part of the said rib.

Upon the under side of the center of the bar A is formed a pivot, D, which is surrounded 50 by a ring-flange, E, as shown in Fig. 4. The

pivot D works in a socket, F, the base of which has a flange, G, formed around it to give it a firm support. The flange G has holes formed through it to receive screws for securing the socket F in place upon the floor. The swing 55 can be used without securing the socket F to the floor, if desired.

Upon the under side of each end of the bar A is formed a pair of lugs, H, to and between which is pivoted a roller, I. The lugs H are 60 arranged in such a position that the axis of the roller I will be upon the radius of a circle having its center in the axis of the pivot D, so that the roller I will roll easily as the bar A is turned upon the said pivot D. 65

J is a small wheel or roller, which is pivoted to and between the arms of a U-shaped bar, K, the loose end of one arm of which projects outward and upward to form a rest or stirrup, L, to receive the chine of the barrel. When the 70 chine of a barrel rests upon the stirrup L the inner arm of the bar K rests against the side of the barrel, and thus holds the roller J in an upright position, so that no fastening will be required to keep the said roller in place. With 75 this construction the axis of the roller J will be upon the radius of the circle having its center in the axis of the pivot D, so that the said roller J will roll easily when the barrel is turned upon the said pivot D. 80

In using the swing the bar A is placed in the position shown in Figs. 1 and 2, and the barrel is rolled upon its chine into such a position that the raised part of the chine can be lowered upon the bar A so as to rest in the 85 notched projections B, and upon the rib C. The barrel and the bar A are then tipped back far enough to allow the stirrup L of the roller J to be placed beneath the chine of the barrel, directly opposite the pivot D, as shown in Figs. 90 1 and 2. The socket F is made enough larger than the pivot D to allow the bar A to be tipped far enough to allow the stirrup L of the roller J to be placed beneath the chine of the said barrel without breaking the said pivot D or 95 causing it to bind in the socket F. With this construction a barrel, however heavy it may be, can be readily turned in beneath a counter, so as to be out of the way, and turned out to give 100 convenient access to its interior, when required.

Having thus fully described my invention, I claim as new and desire to secure by Letters Patent—

5 A barrel-swing constructed, substantially as herein shown and described, of a curved bar, A, having upon its upper side notched projections B, at its ends, a radial rib, C, at its center, rollers I, pivoted between lugs on its under sur-

face, at its ends, and a pivot, D, at its center, the stationary socket E, and the roller J, and its stirrup K L, as set forth.

SYLVESTER W. SHELDON.
